United States Patent Office.

ELIAM BOORSE, OF PHILADELPHIA, PENNSYLVANIA.

Letters Patent No. 96,873, dated November 16, 1869.

IMPROVEMENT IN FASTENINGS FOR FRUIT-JARS.

The Schedule referred to in these Letters Patent and making part of the same.

To all whom it may concern:

Be it known that I, ELIAM BOORSE, of the city and county of Philadelphia, and State of Pennsylvania, have invented a new and useful Improvement in Fruit-Jars; and I do hereby declare the following to be a full, clear, and exact description of the nature thereof, sufficient to enable others skilled in the art to which my invention appertains to make and use the same, reference being had to the accompanying drawings, making part of this specification, in which—

Figure 1 is a side view of the device illustrating my invention.

Figure 2 is a top or plan view thereof.

Similar letters of reference indicate corresponding parts in the two figures.

My invention consists in constructing the locking-cap of a fruit-jar of a series of arms of unequal lengths and forming hooks on their lower ends, which are adapted to take hold of the thread in the neck of the jar, so that by rotating said cap, the arms engage with the thread and draw the cap with them, so that the latter is firmly and securely held in place with the top or cover interposed between the cap and neck, as usual.

In the drawings—

A represents the body of a fruit-jar of ordinary construction, and having its neck formed with a screw-thread, B.

C represents the locking-cap, which is constructed, by preference, of metal, and consists of a top, C', which is of the form of a flat disk or ring, with which are formed a series of arms, D D¹ D² D³.

In the present case, these arms are four in number, and may be cast with or cut out of the same piece with the top C', and are of unequal lengths, their lower ends are bent inwardly or toward each other, and form hooks or catches E.

These arms may be formed separately from the top and subsequently soldered, riveted, or otherwise secured to said top, as most desirable or convenient.

The operation is as follows:

The cap C is placed on the neck of the jar with the longest arm D at the beginning of the thread. A rotation of the cap will cause the arm D to engage with the thread and advance therein. The arm D', and subsequently the other arms, follow the direction and operation of the arm D until the cap cannot be further rotated, which is owing to its arrival or stoppage on the neck of the jar.

It will be found that the cap is firmly held in place on the jar.

Should the thread break at any portion and one or more of the arms be thereby released, the other arms will be found sufficient to hold the cap.

An ordinary top or cover may be interposed between the cap and the neck of the jar, and a rubber band or gasket applied, as ordinarily. In this case, the top C' of the cap may consist of an open ring. If the ordinary top or cover is dispensed with, the top of the cap must be made entire, or in the form of a disk, and the gasket, if employed, must be located between the cap and the neck of the jar.

The arms D D¹ D² may be lengthened, so as to engage with the thread of the neck from their commencement to termination, or the thread may begin at or about the middle of the neck, instead of at its upper end, as shown in the drawings, but these are matters which are subject to desire or necessity.

Having thus described my invention,

What I claim as new, and desire to secure by Letters Patent, is—

As a new article of manufacture, the locking-cap for screw-necked jars, constructed with engaging arms D D¹ D² D³ of unequal lengths, whereby the hooked ends of said arms engage under the same thread and hold at different points thereon, substantially as represented and described, and for the purpose specified.

ELIAM BOORSE.
